(57) **CLAIM**

The ornamental design for an automobile and toy replica thereof, as shown and described.

DESCRIPTION

FIG. 1 is a front perspective view of an automobile and toy replica thereof of our new design;

FIG. 2 is a right side view thereof, the left side view being a mirror image thereof, with the exception of the fuel door which is not present on the left side;

FIG. 3 is a rear perspective view thereof;

FIG. 4 is a front view thereof;

FIG. 5 is a rear view thereof; and,

FIG. 6 is a top plan view thereof.

The bottom view of the automobile and toy replica forms no part of the claimed design.
